Macomb & Ellis,

UNITED STATES PATENT OFFICE.

JOHN D. TAYLOR, OF BUFFALO, NEW YORK, ASSIGNOR, BY MESNE ASSIGNMENTS, TO GENERAL RAILWAY SIGNAL COMPANY, OF BUFFALO, NEW YORK, A CORPORATION OF NEW YORK.

RAILWAY SWITCHING APPARATUS.

No. 832,175.

Specification of Letters Patent.

Patented Oct. 2, 1906.

Application filed January 22, 1904. Renewed February 3, 1906. Serial No. 299,363.

To all whom it may concern:

Be it known that I, JOHN D. TAYLOR, of Buffalo, New York, have invented certain new and useful Improvements in Railway 5 Switching Apparatus, of which the following is a full, clear, and exact description.

My invention relates to railway switching apparatus, and more particularly to such apparatus where electric energy is employed to move and lock the switch and also, according to my previous inventions hereinafter referred to, to give dynamic indication of the complete movement and locking of the switch.

15 My invention is therefore an improvement upon my former inventions shown in Patents No. 605,359, reissued No. 11,983, May 6, 1902, and No. 707,181, August 19, 1902.

The object of my invention is to prevent a 20 false indication; and it consists of what I term an "indication-selector."

Referring to the drawing herewith, consisting of a diagram of the circuits, B is a rail-switch. 1 2 represent the motor for moving the rail-switch. 3 4 5 6 7 8 is a pole-changing switch; 50, a source of energy; 19 20, the brushes of the controller; 29, the indication-magnet, and 30 the safety-magnet, all fully described in my said former patents. 31 and 32 are the indication selector-magnets, and 15 is a tongue acting as an armature and governed by said magnets to make electrical connection with the contacts 36 or 37, as the case may be, and so arranged as to remain in 25 electrical connection with contact 36 or 37 after current has been cut off and until a magnet (31 or 32, as the case may be) has been energized to draw said tongue against the opposite contact.

30 To explain the operation, I will trace the circuits, first showing a normal movement and then showing a false indication due to the "kick" of the rail-switch, and thus explain how my invention prevents a false indication which might otherwise occur.

When it is desired to move the switch B to give access to the siding, the controller is moved to put the brushes 19 and 20 in electrical connection with the contacts 16 and 17 35 and 22 and 23, respectively. This closes a circuit of the battery 50, so that current flows through wires 45 33, safety-magnet 30, wires 37 27, selector-magnet 31, wire 25, con-

tact 17, brush 19, contact 16, wire 6, contact 7, switch-arm 4, wire 9, motor-armature 1, 55 wire 10, switch-arm 3, contact 8, wire 12, contact 6, wire 11, field-coils 2, wires 13 and 35 back to battery. This causes the armature 1 to rotate, and by the mechanism described in my said Letters Patent the rail-switch B is reversed, the lock-bolt is shot, and the pole-changing switch is reversed, so that the switch-arm 3 makes electrical connection with the contact 5 and the switch-arm 4 makes electrical connection with the 60 contact 6. In the meantime this current has energized the magnet 31, and this magnet has moved the tongue 15 out of electrical connection with the contact 37 and into electrical connection with the contact 36. The 65 continued rotation of the motor-armature 1, due to momentum, generates current for dynamic indication, as described in my said former patents, which flows from armature 1 to wire 10, switch-arm 3, contact 5, wire 14, contact 22, brush 20, contact 23, wire 26, contact 36, tongue 15, wire 38, indication-magnet 29, wires 34 57 35 13, field-coils 2, wire 11, contact 6, switch-arm 4, and wire 9 back to motor-armature 1. This gives the proper indication that the switch is home and locked. Now suppose the rail-switch is set for the siding and the operator desires to set it for the main track. In that condition the pole-changing switch will have the arms 3 and 4 70 in electrical connection with the contacts 5 and 6, respectively. The operator now moves the controller so that the brush 20 makes electrical connection between the contacts 22 and 39. Current then flows from 75 the battery 50 through wires 45 33, magnet 30, wires 37 28, magnet 32, wire 21, contact 39, brush 20, contact 22, wire 14, contact 5, switch-arm 3, wire 10, motor-armature 1, wire 9, switch-arm 4, contact 6, wire 11, 80 field-coils 2, wires 13 35 back to battery 50. This causes movement of the rail-switch toward the position for the main track; but suppose at this time the rail-switch meets an obstacle which prevents it from going to its 85 final position, so that it is locked and the pole-changing switch reversed, and suppose that then the operator reverses the controller and breaks the battery-circuit between the contacts 22 and 29. The kick or recoil of 90 the rail-switch may cause the motor-arma-

ture 1 to revolve in the opposite direction and generate a current which would flow from the motor-armature 1 through wire 9, switch-arm 4, contact 6, wire 11, field-coils 2, wires 5 13 35 57 34, magnet 29, wire 38, tongue 15, contact 36, wire 26, contact 23, brush 20, contact 22, wire 14, contact 5, switch-arm 3, and wire 10 back to motor-armature. This would produce a false indication were it not 10 for the fact that while battery-current was flowing to move the rail-switch such current has energized the magnet 32 and moved the tongue 15 out of electrical connection with the contact 36, and since connection is 15 broken between the contacts 16 and 17 by the movement of the controller last described the other indication-path is broken. In this manner a false indication is prevented in the event of failure of the switch to go home and 20 the reversal of the controller.

Having thus described my invention and its method of operation, what I claim is—

1. In combination with a source of energy, a motor, operating and indicating circuits, a 25 controller, a pole-changing switch, an electromagnetic indication-selector comprising magnets in the branches of the operating-wire, a tongue in the indicating common governed by said magnets, a motor, an indication-magnet, a pole-changing switch governed by the 30 relay-switch, whereby the operating-current through one of said selector-magnets closes the indicating common with the proper branch of the indicating-wire, substantially 35 as and for the purposes set forth.

2. In combination with a source of energy, a motor, a circuit-breaking or pole-changing device actuated by said motor, operating and indication circuits, an electric switch for making suitable connections between said 40 source of energy and said indicating and operating circuits, an electromagnetic device actuated or controlled by the operating-current, whereby the normal indication is closed when said electric switch is moved normal, 45 and whereby the reverse indication-circuit is closed when said electric switch is moved to reverse position, substantially as and for the purposes set forth.

3. In combination with a source of energy, 50 a motor, a controller, a wire leading from one pole of said source of energy to said motor, a wire leading from the opposite pole of said source of energy to the opposite pole of said motor, a pole-changing switch for reversing 55 the electrical connections with said motor, a controller in said circuits, an indication-circuit, an electromagnetic switch energized through the operating-circuit to establish the proper indication-circuit on each movement 60 of said controller and prior to the dynamic indication from said motor, substantially as and for the purposes set forth.

In witness whereof I have hereunto set my hand in the presence of two witnesses.

JOHN D. TAYLOR.
